Allen Lee Wilbiss Jr

UNITED STATES PATENT OFFICE.

ALLEN DE VILBISS, JR., OF TOLEDO, OHIO.

SCALE.

SPECIFICATION forming part of Letters Patent No. 621,297, dated March 14, 1899.

Application filed December 13, 1897. Serial No. 661,636. (No model.)

To all whom it may concern:

Be it known that I, ALLEN DE VILBISS, Jr., a citizen of the United States, residing at Toledo, in the county of Lucas and State of Ohio, have invented certain new and useful Improvements in Scales; and I do hereby declare the following to be a full, clear, and exact description of the invention, such as will enable others skilled in the art to which it appertains to make and use the same.

This invention relates to scales, and more especially to that class thereof employing pendulums; and the object of the same is principally to produce a scale of this character whose hand or index swings in irregular steps as weight is added to the pan or platform over a straight-line table whose graduations or marks are equidistant.

Other objects are also attained, such as the simplicity of construction, the provision of several adjustments, the adaptability of the one scale to heavier or lighter work, and the like.

To this end the invention consists in a construction embodying the features hereinafter described and claimed, whether in the exact or any equivalent form, and as illustrated in the drawings, wherein—

Figure 1 is a side elevation of this improved scale complete, showing it of the "pan" type, although it will be clear that it might be of the "platform" pattern, if desired. Fig. 2 is a similar elevation with the front of the casing removed to show the interior mechanism. Figs. 3 and 4 are plan views, the first with and the second without the pan. Fig. 5 is a vertical section on line G of Fig. 2, and Fig. 6 is an elevation of a modification.

Referring to the drawings by reference-letters, A designates the scale-beam, fulcrumed within the casing or housing in the usual manner, as on a knife-edge B, and C is a second pivot or knife-edge, which in the present instance supports the bail M of the pan R, although it will be clear that by a slight change in structure the well-known platform could be substituted for the pan without departing from the spirit of my invention. Nothing new is claimed for this much of the device.

E is a bracket of any suitable character fast

within the housing, and D is the poise, pivoted at D' to this bracket and hanging normally vertical within the housing, although capable of swinging outward through a slot 55 therein, as seen. The poise consists of a pendulum preferably marked with graduations, an adjustable weight J, moving thereover for a purpose to appear below, and an arm N, projecting laterally from the pendulum adjacent but below its pivot D'.

F is a connection of any suitable character between the inner end of the beam A and the outer end of the arm N.

In the modification illustrated in Fig. 6 the weight J' may be non-adjustable, and the arm N' is longitudinally slotted, as seen, so as to receive an adjustable block F', to which the lower end of the connecting-rod F is pivoted. In this case the arm would be provided with 70 the graduations, and the adjustment of the block farther from or nearer to the pivot D' would have substantially the same effect as the adjustment of the weight J of Fig. 2, either form of adjustment causing the poise 75 to have greater or less resisting power, and hence to swing through smaller or larger arcs.

H is a hand or index, of any suitable light material and which is rigidly secured to the poise at its pivotal point D'. It preferably 80 extends slightly below the same and carries a counterweight I, and it rises above the pivot within the housing, as seen. Said housing also carries a scale or table L of any suitable character and preferably protected by glass, 85 and the graduations of this table are equidistant from each other, as seen, while they extend in a perfectly straight horizontal line across the upper part of the housing. In swinging, the index H moves across said graduations in an upward-bowed arc, and hence the graduations are preferably marked on lines radiating from the point D'; but it is essential that they be equidistant from each other, as shown.

All parts of this improved scale are of the desired materials, sizes, and proportions, and such changes in construction may be adopted as come within the spirit of my invention. I do not wish to be limited as to details excepting as set forth above and in order to produce the proper operation of the whole. The ta-

ble is preferably inscribed with rows of graduations indicating pounds (or the like) and fractions thereof, as well as prices, and when the latter are used the weight on the poise 5 can be set at any desired price per pound and the graduations read for the aggregate. However, I reserve the privilege of using any desired marking adjacent all the graduations mentioned herein.

10 The parts being constructed about as above set forth and standing at rest, as seen in Fig. 2, the placing of one pound on the pan R will cause the tilting of the beam A and through connection F and arm N will swing the poise

15 D to the left one step. Since the index II is attached to the poise and projects above its pivot D', it will therefore be swung to the right one step. The successive addition to the pan of other pounds will similarly move

20 the parts, though in irregular steps, the reason being that as the pendulum D rises the arm N approaches the horizontal line of the pivot D' and gains leverage more rapidly than the pendulum gains weight. After passing said

25 horizontal line the arm N loses power, while the pendulum in its continued rise gains further weight. Hence through the first portion of this operation the length of the steps increases, and through the latter portion it

30 decreases, so that if the table L were curved to conform with the movement of the index II around the center D' its graduations would necessarily be irregularly spaced. I have found by practical experiment, however, that

35 if the graduations at L are arranged in a perfectly straight line which is a chord of the arc through which any given point on the index moves the variable distance between the steps on the arc is just such that the steps on

40 the straight line are uniform, and the graduations if placed adjacent or upon said line will be truly equidistant. If this is true of one straight line, it is true of another so long as it is a chord of said arc, and hence I may use

45 several lines to indicate varying prices and weights. Nor is this rule inoperative if the poise be rendered heavier or lighter, (as by adjusting weight J on pendulum D or block F' in the slot of arm N,) although the steps

50 will thereafter be relatively shorter or longer, and other lines in the table will be used. Hence by means of the adjustment described

the range of action of the scale may be increased or diminished.

What is claimed as new is—

55

1. In a scale, the combination with the beam, the pan carried thereby, the poise, and connections between the beam and poise for causing the swinging of the latter in irregular steps as weight is added to the pan; of an index secured to the poise and projecting from the pivot thereof, and a straight table having regularly-spaced graduations over which the index moves, substantially as described.

65

2. In a scale, the combination with the beam, the pan carried thereby, the poise having a lateral arm adjacent its pivot, and connections between said beam and arm for moving the outer end of the arm past the pivot 70 of the poise and causing the swinging of the latter in irregular steps as weight is added to the pan; of an index connected and turning with the poise around the pivot thereof, and a straight table having regularly-spaced 75 graduations over which the index moves, substantially as described.

75

3. In a scale, the combination with the beam, the pan carried thereby, the pendulum, a weight adjustable on the pendulum, 80 and connections between the beam and pendulum for causing the swinging of the latter; of an index rigidly secured to the pendulum and projecting from the pivot thereof, and a straight-line computing-table having a plurality of rows of graduations over which said 85 index moves, substantially as described.

85

4. In a scale, the combination with the beam, the pan carried thereby, the pendulum, a weight adjustable on the latter, and 90 graduations thereon for setting the weight to regulate the degree of movement of the pendulum; of connections between the beam and pendulum for causing the swinging of the latter, an index mounted on the pendulum, 95 and a straight-line computing-table having regularly-spaced graduations over which said index moves, substantially as described.

95

In testimony whereof I have affixed my signature in presence of two witnesses.

ALLEN DE VILBISS, JR.
